UNITED STATES PATENT OFFICE.

JOHN RAUS, OF CLEVELAND, OHIO, ASSIGNOR TO THE OHIO INSTRUMENT MANUFACTURING COMPANY, OF CLEVELAND, OHIO, A CORPORATION OF OHIO.

ELECTRICAL CONNECTOR.

1,418,468.

Specification of Letters Patent. Patented June 6, 1922.

Application filed August 22, 1919. Serial No. 319,056.

To all whom it may concern:

Be it known that I, JOHN RAUS, a citizen of the United States, residing at Cleveland, in the county of Cuyahoga and State of Ohio, have invented a certain new and useful Improvement in Electrical Connectors, of which the following is a full, clear, and exact description, reference being had to the accompanying drawings.

10 This invention relates to electrical connectors and more particularly to a connector for fastening a wire to another conductor to make electrical contact therewith and has for its objects the provision of a connector 15 which will make positive electrical contact at all times without injury to the wire; which shall be free from projecting parts; which shall consist of few parts and those of easy and inexpensive manufacture; which 20 shall be easily adjusted for gripping or unfastening the wire; while further objects and advantages will appear as the description proceeds.

In the accompanying drawing where I 25 have shown certain illustrative embodiments of my said invention, but without intent to limit myself thereto, Fig. 1 is a side elevation of one half of an electrical connector in common use and to which my invention 30 may be applied; Fig. 2 is a similar view but at right angles to Fig. 1 and with the insulating sleeve removed; Fig. 3 is an enlarged longitudinal section of Fig. 2 showing the method of connecting the wires; Fig. 4 is 35 an enlarged sectional view showing the manner in which the wire is fastened to the conductor; Fig. 5 is a plan view of the gripping member partly formed; Fig. 6 is a side elevation of the gripping member in the 40 finished form; Fig. 7 is a side elevation, with parts broken away, of the gripping member and adjusting bushing therefor; Fig. 8 is a side elevation of a wire connector to which my invention has been applied and Fig. 9 illustrates my invention applied as a binding post on a dry battery.

Describing the various parts by reference numerals, 1 indicates the entering half of an electrical connector of the bayonet type 50 which has the contact rods 2 imbedded in the insulating material with their longitudinal axes parallel to the longitudinal axis of the connector. The rear end of each of the rods 2 is formed with a socket having its 55 inner part tapered as at 4 and its outer part

threaded as at 5 to receive a bushing 6, having a suitable head 8 such as a hexagon so as to be readily turned with a pair of pliers or wrench. If desirable the head 8 may be round and have a knurled edge so as to be 60 readily turned by the fingers.

The bushing 6 is formed with a bore 7 and its inner end is counterbored to form a seat 9 for the body 10 of the gripping member. The gripping member may be 65 formed by stamping a blank of the desired shape, as shown in Fig. 5, from sheet metal, then punching the hole 11 and at the same time drawing the central portion to form the tubular body 10 and bending the legs 70 12 together to form the finished product, shown in Fig. 6. The legs 12 are preferably arcuate in cross section, so as to conform to the surface of the wire, and this may be accomplished during the stamping operation. 75

In assembling the parts the body 10 of the gripping member is fitted into the seat 9 of the bushing which is in turn screwed into the threaded portion 5 of the socket a few 80 turns. The bared end of the wire is then passed through the hole 7 of the bushing and 11 of the gripping member, (it being understood that these holes are in alignment) and down to the bottom of the tapered socket. The bushing is now tightened down which brings the legs 12 into contact with the tapered walls of the socket and forces them together so as to grip the wire. It will also be noted that the legs 12 tend to 85 push the wire forwardly during this clamping process thereby insuring perfect electrical contact and a tight connection.

In Figs. 8 and 9 I have shown some of the many uses to which my connector may be 90 applied. Fig. 8 represents a connector for two wires and consists of a suitable rod 13 provided at each end with the bushing and gripping members previously described. Fig. 9 shows my device applied to the terminals of a dry battery. 100

It will be understood that the foregoing are only a few of the many physical forms in which my invention can be embodied and that many changes can be made within the 105 scope of my claims.

Having thus described my invention, what I claim is:

1. An electrical connector comprising an externally threaded, longitudinally bored, 110

- entering member having legs projecting from the inner end and arranged symmetrically about the axis of said bore, and a receiving member having a threaded portion to receive the threads of the entering members and a tapered portion terminating in a seat to receive and converge the ends of said legs against a wire to force said wire into said seat.
- 10 2. In an electrical connector the combination with a receiving member having a tapered socket adapted to have a wire bottomed therein, of a gripping member having legs adapted to enter said socket between said wire and the tapered wall, and means surrounding said wire for forcing said gripping member into said socket to converge the legs thereof against said wire and force said wire against the bottom of said socket.
- 15 3. An electrical connector comprising a receiving member having a tapered bore terminating in a seat, a gripping member positioned in said bore and having a plurality of legs the ends of which are adapted to engage the walls of said tapered bore, and means for forcing said gripping member inwardly to cause the ends of said legs to engage a wire and force it to the seat of said tapered bore.
- 20 4. An electrical connector comprising a receiving member having a tapered bore terminating in a seat, a gripping member having a body portion contacting with said member and a plurality of legs extending therefrom and contacting at the ends thereof with the walls of said tapered bore, said bushing and gripping member being provided each with a longitudinal bore to receive a wire and said gripping member being adapted to engage said wire to force it to the seat of said tapered bore upon rotation of said bushing member.
- 25 5. An electric conductor comprising a receiving member having a tapered bore terminating in a seat; a gripping member seated in said bore; said gripping member comprising a bushing having a bore coaxial with the tapered bore; resilient gripping fingers projecting from the gripping member and arranged about the bore therethrough so spaced as to be normally out of contact with a wire passed through said bore; and means for forcing the ends of said gripping fingers inwardly so as to cause them to contact with the wire at an angle to the axis thereof and to force the end of the wire in said seat.

In testimony whereof, I hereunto affix my signature.

JOHN RAUS.
